UNITED STATES PATENT OFFICE.

HERBERT S. JANDUS, OF DETROIT, MICHIGAN, ASSIGNOR TO THE C. G. SPRING & BUMPER COMPANY, OF DETROIT, MICHIGAN, A CORPORATION OF DELAWARE.

DESIGN FOR A CLAMP PLATE FOR VEHICLE BUMPERS.

Application filed June 17, 1927. Serial No. 22,481. Term of patent 14 years.

To all whom it may concern:

Be it known that I, HERBERT S. JANDUS, a citizen of the United States, residing at Detroit, in the county of Wayne and State of Michigan, have invented a new, original, and ornamental Design for a Clamp Plate for Vehicle Bumpers, of which the following is a specification, reference being had to the accompanying drawing, forming part hereof, wherein—

Fig. 1 represents, a front elevation and Fig. 2 a side elevation of a clamp plate for vehicle bumpers exhibiting my new design.

I claim:

The ornamental design for a clamp plate for vehicle bumpers, substantially as shown.

HERBERT S. JANDUS.
